UNITED STATES PATENT OFFICE

2,607,638

ROLLER-BEARING RAILWAY CAR AXLE
CONSTRUCTIONRalph E. Horger, Canton, Ohio, assignor to The
Timken Roller Bearing Company, Canton,
Ohio, a corporation of Ohio

Application November 14, 1947, Serial No. 786,111

4 Claims. (Cl. 308—180)

1

This invention relates principally to roller bearing railway car axle constructions of the kind shown in my copending application Serial No. 536,669, now Patent No. 2,438,214, wherein the roller bearings are enclosed in an oil containing housing mounted on the axle, a journal box seats on the housing and encloses the same, and the housing is provided at its outer end with an oil filler opening to which access is had through the opening in the corresponding end of the journal box.

The principal object of the present invention is to provide means visible through the access opening in the journal box and the oil filler opening in the bearing housing for indicating the maximum oil level in the latter, to provide a hinged lid for said opening which will prevent water and dirt from draining into said opening, and to enable the lid to be easily opened through the access opening in the journal box. The invention consists in the lubricated roller bearing railway car axle construction and in the parts and combinations and arrangements of parts hereinafter claimed.

In the accompanying drawings, which form part of this specification and wherein like symbols refer to like parts wherever they occur.

Fig. 1 is a central vertical longitudinal sectional view of a roller bearing railway car axle construction embodying my invention.

Fig. 2 is a fragmentary sectional view similar to Fig. 1, showing the lid for the oil filler opening in the bearing housing in opened position.

Fig. 3 is a vertical cross-sectional view on the line 3—3 in Fig. 1.

Fig. 4 is a fragmentary cross-sectional view on the line 4—4 in Fig. 2.

Fig. 5 is a front elevational view of the lid for the oil filler opening; and

Fig. 6 is an inside view of said lid.

My invention is shown embodied in a roller bearing railway car axle and journal box assembly of the kind shown in my copending application Serial No. 536,669, filed May 22, 1944. Said construction comprises a conventional plain bearing journal box A having an enlarged dust guard opening 1 in the inner end thereof and the usual hinged lid 2 for covering the access opening 3 in the outer end thereof, an axle B having a journal portion extending into said journal box through said dust guard opening, and a car wheel C rigid with said axle inwardly of said journal box.

The above axle and journal box assembly is provided with a rotary antifriction bearing con-

2

struction, which preferably comprises two axially spaced tapered roller bearings 4 mounted on the axle B and enclosed in a tubular non-rotary oil containing housing or cartridge D. The dust guard opening 1 in the inner end of the journal box A is large enough to permit passage of the roller bearing housing D through said opening; and the top of said journal box seats on the top of said housing which is longitudinally curved after the manner of the usual plain bearing journal box wedge.

The outer end of the bearing housing D is closed by means of a closure plate 5 that is removably secured to said end of said housing by means of cap screws 6. Escape of oil from and entry of dust into the inner end of the bearing housing are prevented by means of an annular closure plate or ring 7 that is secured flatwise to the inner end of said housing by means of cap screws 8 and encircles the outer end of a backing ring 9 which is sleeved on the axle B and seats against a tapered shoulder thereon and is disposed in endwise abutting relation to the inner end of the inner raceway member of the innermost taper roller bearing.

The lower portion of the removable outer end wall 5 of the bearing housing D has a hollow outstanding ledge portion 10 which forms a horizontal oil pocket 11 which opens into said end of said housing adjacent to the bottom thereof.

The hollow outstanding ledge portion 10 of the closure plate 5 has a downwardly and outwardly inclined front wall 12, in which is formed a horizontally elongated oil filler and observation opening 13, the mouth or entrance of which is defined by a continuous outstanding rib 14 formed on said inclined front wall and forming a flat seat around said opening. Formed integral with the inclined front wall portion 12 of the hollow outstanding ledge portion 10 of the outer end closure plate 5 is a lug which projects inwardly into the pocket 11 formed by said hollow ledge portion from the lower edge of the oil filler and inspection opening 12 and tapers both horizontally and vertically to form an arrowhead pointer or indicator 15. The arrowhead pointer 15 is spaced above the bottom of the oil pocket 11 and indicates the maximum level for the oil in the bearing housing D. Furthermore, as shown in Figs. 1 and 2, the ledge portion 10 has its inner bottom surface above the bottom of the housing D so that oil just reaching the ledge and visible at the opening 12 will be an indication of the lowest or minimum allowable oil content of the housing.

The mouth of the oil filler and observation

opening 13 in the outer end closure plate 5 for the bearing housing D is covered by a spring-closed horizontally hinged lid 16 which seats flatwise on the raised flat bearing surface provided therefor on the continuous outstanding rib 14 around the oil filler opening 13 and has a lip 17 that overhangs the portions of said rib that extend along the top and ends of said opening. The lid 16 has a pair of horizontally spaced hinge lugs 18 formed on the upper edge thereof that are bored to receive a horizontal hinge pin 19 whose ends are supported in axially aligned horizontal bores provided therefor in a pair of outstanding supporting lugs 20 on the front face of the closure plate just above the inclined front wall 12 of the outstanding ledge portion 10 thereof, the ends of said hinge pin being riveted over, as at 19a, on the remote faces of said supporting lugs.

The lid 16 is closed by a double torsion spring 21 comprising two axially spaced reversely wound helically coiled portions 22 that are sleeved on the hinge pin 19 between the hinge lugs 18 of the lid and are connected by a depending loop portion 23, which bears against the top of said lid, and terminate in straight outer end portions 24 that extend upwardly between said hinge pin and the end closure plate 5 and bear against the latter. The lid 16 has cylindrical portions 25 integral therewith that extend horizontally therefrom on opposite ends thereof and terminate at their outer ends in heads or collars 26.

By the arrangement described, the bearing housing D may be supplied with oil through the oil filler opening 13 in the hollow outstanding ledge portion 10 of the end closure plate 5 for said housing, access being had to said opening through the opening 3 in the outer end of the journal box A. The arrowhead pointer 15 at the lower edge of the oil filler opening extends into the oil pocket 11 in the hollow outstanding ledge portion 10 of the end closure plate 5 and indicates the maximum level of the oil in the bearing housing D; and such level may be observed through the access opening 3 in the journal box A and through said oil filler opening when the lids for said openings are raised. The spring closed lid 16 for the oil filler opening 13 may be raised by inserting a standard waste packing bar through the access opening 3 in the journal box and engaging said bar with either one of the cylindrical extensions 25 at the ends of said lid, the bar being prevented from slipping off said extensions by the heads 26 thereof. The double coiled torsion spring 21 serves to seat the lid 16 tightly on the raised flat bearing surface formed by the outstanding rib 14 which surrounds the oil filler opening 13, and the lip 17 of said lid overhangs the upper and end portions of said rib and serves to deflect water or dirt from said opening.

Obviously, the hereinbefore described axle, journal box and roller bearing housing assembly admits of considerable modification without departing from my invention. Therefore, I do not wish to be limited to the precise arrangements shown and described.

What I claim is:

1. A railway roller bearing axle and journal box assembly comprising an axle, a rotary anti-friction bearing mounted on said axle, an oil containing housing for said bearing, a journal box enclosing said housing, and a removable closure plate for the outer end of said housing having a hollow outstanding ledge portion opening into the lower portion thereof, said ledge portion having an interior bottom surface disposed 5 at the lowest allowable level for the oil in said housing and a downwardly and outwardly inclined front wall with an oil filler opening therein, said journal box having an opening in its outer end through which access may be had to said filler opening, said hollow ledge portion having means therein adjacent to the lower edge of said filler opening and visible through the access opening in said journal box and the filler opening in said housing for indicating the maximum desired level of the oil in the latter.

2. The combination set forth in claim 1 wherein said maximum desired oil level indicating means comprises an indicator permanently located in said hollow outstanding ledge adjacent to the lower edge of said oil filler opening.

3. The combination set forth in claim 1 wherein said maximum desired oil level indicating means comprising a pointer extending inwardly into said hollow outstanding ledge from the lower edge of the oil filler opening and spaced above said interior bottom surface thereof.

4. A railway roller bearing axle and journal box assembly comprising an axle, a rotary anti-friction bearing mounted on said axle, an oil containing housing for said bearing, a journal box enclosing said housing, and a removable closure plate for the outer end of said housing to retain the oil in the housing, said closure plate having a pocket adjacent the bottom thereof defined by a generally horizontally and outwardly directed ledge portion arranged relatively above the bottom of said oil containing housing, said pocket also being defined by a downwardly and outwardly inclined wall providing an opening for the introduction of oil and the sight inspection of the oil standing on said ledge portion, said journal box having an opening in its outer end through which access is had to said inclined wall opening, and an oil level indicating pointer positioned inwardly of said inclined wall opening to be visible through the latter opening and the opening in the outer end of said journal box.

RALPH E. HORGER.
